(57) **CLAIM**

The ornamental design for a cradle for communications device, as shown and described.

DESCRIPTION

FIG. 1 is an isometric front view of a cradle for communications device showing the new design;

FIG. 2 is a front view of the design of FIG. 1;

FIG. 3 is a right side view of the design of FIG. 1;

FIG. 4 is a left side view of the design of FIG. 1;

FIG. 5 is a top view of the design of FIG. 1;

FIG. 6 is a bottom view of the design of FIG. 1;

FIG. 7 is a back view of the design of FIG. 1;

FIG. 8 is a an isometric back view of the design of FIG. 1;

FIG. 9 is an isometric front view of a cradle for communications device showing an alternative embodiment of the new design;

FIG. 10 is a front view of the design of FIG. 9;

FIG. 11 is a right side view of the design of FIG. 9;

FIG. 12 is a left side view of the design of FIG. 9;

FIG. 13 is a top view of the design of FIG. 9;

FIG. 14 is a bottom view of the design of FIG. 9;

FIG. 15 is a back view of the design of FIG. 9; and,

FIG. 16 is a an isometric back view of the design of FIG. 9.

The broken lines showing of selected portions of the cradle for communications device depict environmental subject matter and forms no part of the claimed design.

1 Claim, 14 Drawing Sheets
